UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN FIXTURE.

Application filed June 5, 1924. Serial No. 717,921.

This invention relates to the art of curtain fixtures, and has reference more particularly to an improved means for yieldably attaching the ends of the curtain rod to the supporting brackets thereof. The present improvement belongs to that class of curtain fixtures which employ so-called "flat" rods, and the chief object of the invention is to provide a very simple, cheap and efficient construction of rod and bracket whereby the ends of the rod may be readily entered on the bracket and yieldably locked thereto with capacity for removal when required by a pull sufficient to disengage them. Various fastening devices of this general character are known, many of which involve the application to the bracket or curtain rod of extraneous fastening devices. By my present invention, the cooperating devices by which the rod is yieldably locked on the bracket constitute integral parts of the rod and bracket themselves and involve no attachments.

In order that the invention may be clearly understood by persons skilled in the art, I have illustrated in the accompanying drawings two practical and simple embodiments of the principle of the invention, and referring thereto—

Fig. 1 is an inner side elevation of a rod-supporting bracket and one end of a flat curtain rod engaged therewith;

Fig. 2 is a top plan view, partly in section through the end portion of the rod on the line 2—2 of Fig. 1;

Fig. 3 is a vertical transverse section on the line 3—3 of Fig. 1;

Fig. 4 is a view similar to Fig. 1, illustrating a slightly different form of the invention;

Fig. 5 is a view similar to Fig. 2, with the end of the rod in horizontal section on the line 5—5 of Fig. 4;

Fig. 6 is a view similar to Fig. 3, taken on the line 6—6 of Fig. 4; and

Fig. 7 is a perspective detail of the bracket. Referring to the drawing, 10 designates as an entirety a flat sheet metal curtain rod which, as usual in rods of this type, is formed with rearwardly and inwardly curled flanges 11 and 12 on its upper and lower margins respectively. A slight distance inwardly of each end of the rod, portions of these flanges are swaged inwardly, or otherwise depressed toward the body of the rod, as shown at 13

and 14. Preferably, and as herein shown, the body of the rod is indented at a point opposite the inwardly swaged portions of the flanges, thereby producing a protuberance 15 on the rear surface of the rod that is located substantially midway between the depressed portions 13 and 14.

16 designates the bracket arm which is a plain flat strip of metal equipped with a base or attaching flange 17 for application to the window or door casing. The upper and lower edges of the arm 16 are formed with notches 18 and 19, respectively, so shaped as to provide vertical shoulders 20 and 21 (Fig. 7) at the forward ends of the notches 18 and 19, respectively.

The end portion of the rod is applied to the bracket by simply telescoping it over the latter, during which operation the head portion of the bracket arm lying beyond the notches 18 and 19 is forced between the depressed lips 13 and 14 of the flanges and the opposed swell or protuberance 15 of the body, until the head is passed beyond the lips 13 and 14. This is permitted by the transverse resiliency of the metal which, in the construction shown, yields transversely between the central protuberance 15 and the free edges of the depressed lips 13 and 14. When the rod is fully mounted on the bracket arm, the lips 13 and 14 snap into register with the notches 18 and 19, and the shoulders 20 and 21, bearing upon the convex inner surfaces of the lips 13 and 14, yieldably lock the rod on the bracket arm. By a sufficient pull, however, the resilient locking effect of the lips 13 and 14 may be overcome, and the ends of the rod slid off the brackets.

It will be observed by reference to Fig. 2 that the inwardly swaged lips 13 and 14 present a steeper arm-engaging surface at their forward ends than at their rear ends, so that less force is required to apply the rod than to withdraw it.

In the construction illustrated in Figs. 4, 5 and 6, the flanges 11 and 12 are longitudinally slotted parallel with their free edges, as shown at 22 and 23 in Fig. 4, and the slotted portions are then depressed to provide lips 13' and 14' which are functionally analogous to the lips 13 and 14 of Figs. 1, 2 and 3 in respect to their manner of interlocking engagement with the bracket arm. In this construction, however, the central body protuberance 15 may be

omitted, and the resiliency of the lips 13' and 14' alone depended upon to obtain the yieldable interlocking engagement of the rod with the bracket arm.

5 So far as I am aware I am the first to provide yieldable interlocking means for a flat curtain rod and its supporting bracket wherein the upper and lower flanges of the rod provide one of the interlocking elements 10 operative through the transverse resiliency of the flanges. It is manifest that this principle may be embodied in other specifically different forms from those shown and described; and hence I reserve such other 15 variations and modifications of this principle not herein shown as fall within the spirit and purview of the appended claims.

I claim—

20 1. In a curtain fixture, the combination of a flat rod of resilient material formed with rearwardly and inwardly bent flanges on its upper and lower edges, portions of said flanges inwardly of each end of the rod being depressed toward the body of the rod, and a rod-supporting bracket arm telescoping within an end of said rod and formed with shoulders adapted to yieldably 25 interlock behind said depressed portions of the flanges.

30 2. In a curtain fixture, the combination of a flat sheet metal rod formed with transversely resilient rearwardly and inwardly curled upper and lower marginal flanges, opposed portions of said flanges inwardly of each end of the rod being depressed toward the body of the rod, and a flat bracket 35

arm telescoping within an end of said rod and formed with notches in its upper and lower edges adapted to yieldably interlock with said depressed portions of the flanges. 40

3. In a curtain fixture, the combination of a flat sheet metal rod formed with transversely resilient rearwardly and inwardly bent upper and lower marginal flanges, opposed portions of said flanges inwardly of each end of the rod being swaged inwardly 45 toward the body of the rod and the body of the rod being provided with a protuberance on its rear side between said inwardly swaged portions, and a rod-supporting bracket arm telescoping within an end of said rod and formed with shoulders adapted to yieldably interlock behind said inwardly swaged portions of the flanges. 50

4. In a curtain fixture, the combination of a flat sheet metal rod formed with transversely resilient rearwardly and inwardly curled upper and lower marginal flanges, opposed portions of said flanges inwardly of each end of the rod being swaged inwardly toward the body of the rod and the body of the rod being centrally indented to form a protuberance on its rear side between said inwardly swaged portions, and a flat bracket arm telescoping within an end of said rod and formed with notches on its upper and lower edges adapted, under the transverse resiliency of said rod and its flanges, to yieldably interlock with said inwardly swaged portions of the flanges. 65

JAMES H. BOYE.
